CARBURETOR

Filed April 26, 1926

INVENTOR.

Peter Gwisdalla

BY

Thos. Barnell
ATTORNEY.

UNITED STATES PATENT OFFICE

PETER GWISDALLA, OF MINDEN CITY, MICHIGAN

CARBURETOR

Application filed April 26, 1926. Serial No. 104,537.

My invention relates to a new and useful improvement in a carburetor and comprises an improvement on my invention set forth in my application for Letters Patent of the 5 United States, filed November 12th, 1925, Serial No. 68,521, which has matured into Patent No. 1,728,730, issued Sept. 17, 1929.

The object of the present invention is the forming of the carburetor in such a manner 10 that the slidably mounted control disc may operate in the shell or bowl of the carburetor, the shell or bowl forming cylinder walls for co-operating with the disc.

Another object of the invention is the 15 provision in the carburetor of auxiliary fuel control means operable upon the movement of the throttle beyond a predetermined distance for admitting through the auxiliary control means fuel to the carburetor, so that 20 when the engine is run at the maximum speed for the amount of fuel admitted through the primary control additional fuel may be admitted through the secondary or auxiliary control to permit of a greater 25 speed and render the carburetor more efficient in its functions.

Another object of the present invention is the provision of a primary and secondary fuel control means on the carburetor co- 30 operating with each other with a resultant economy in fuel consumption.

Other objects will appear hereinafter.

The invention consists in the combination and arrangement of parts hereinafter described and claimed.

The invention will be best understood from a reference to the accompanying drawings which form a part of the specification and in which

40 Fig. 1 is a central vertical sectional view of the invention.

Fig. 2 is a view taken on substantially line 2—2 of Fig. 1.

45 Fig. 3 is a fragmentary side elevational view of the invention.

Fig. 4 is a fragmentary side elevational view of the invention taken from the side opposite the side shown in Fig. 3.

50 Fig. 5 is a fragmentary sectional view taken on substantially line 5—5 of Fig. 1.

As shown in the drawings the main body of the carburetor is formed preferably from a single casting and comprises a shell or bowl forming portion 11 communicating with the mixing chamber 12 positioned 55 thereabove. Extending laterally outwardly from the chamber 12 is the delivery conduit 13 having the angularly turned portion 14 which is adapted for connection in communication with the intake manifold of the 60 engine. Projecting laterally outwardly from the bowl 11 is a conduit 17 which serves to deliver the air to the carburetor. A plurality of ribs 15 are formed in the 65 interior of the mixing chamber 12 and similar ribs 16 are formed on the inner surface of the bowl portion 11. Secured to the bottom of the portion 11 is a suitable cap or closure 18 and extending around the lower portion of the bowl 11 is a circumferential flange 19. Positioned axially in the bowl 11 and the mixing chamber 12 is a shaft or stem 20, slidably mounted upon which is a disc 21 having a downwardly directed collar 22. A spiral spring engages 70 at one end the disc 21 and at its opposite end a collar 24 which is mounted upon the stem 20. Mounted upon the upper portion of the mixing chamber 12 is a cap 25 having a fuel inlet chamber 26 formed therein. 75 Projecting from one side of the cap 25 is a nipple 27 which is adapted for connection to a suitable source of fuel supply and communicates through the passage 28 and the 80 passages 29 with the chamber 26. Projecting from the cap 25 is a nipple 30 which communicates through the passage 31 with the chamber 26. Projecting from the cap 25 is a nipple 32 in which is positioned the 85 needle valve 33 adapted upon the threading of the threaded head 34 in the nipple 32 to open and close communication of the passage 28 with the delivery nipple 27. A cap 35 is provided for threading on the nipple 32 so that when the nipple valve 90 33 is adjusted to its proper position to admit a certain amount of fuel through the passage 28 the cap 35 may be positioned on the nipple 32 preventing dust or other accumulations to interfere with the proper 95 100

operation of the head 34 and to render undue tampering with the head 34 difficult.

A needle valve 36 is provided for controlling communication of the passage 31 with the fuel delivery nipple 27, this needle valve 36 having a threaded head which threads into the nipple 30 so that adjustment of the needle valve may be effected to admit, through the passage 31 into the chamber 26, a certain amount of fuel. A cap 38 is also provided for the nipple 30. A nipple 39' projects outwardly from the head 25 in alignment with the nipple 32 and is provided with a bore in which is inserted the stem 39 carrying the threaded head 40 adapted for threading in the nipple 39'. This head 40 is provided with a coarse thread so that the longitudinal movement of the stem 39 to a marked degree is effected upon a slight threading of the head 40. As shown in Fig. 2 this stem 39 may be used to close communication between the passages 28 and the passages 29 and under ordinary operating conditions when the vehicle is being driven below a certain speed this would be the normal position of the stem 39, as no fuel is admitted into the chamber 36 through the passages 28 and 29 until the consumption of fuel by the engine reaches a certain amount. Threaded on the nipple 39' is a cap 41, through which the stem 39 projects. Threaded into the cap 25 is a seat forming portion 42 through which projects the reduced portion 43 of the shaft or stem 20. Mounted upon the upper end of the reduced portion 43 is a valve head 44 for engaging the seat 42, this valve head 44, when in engagement with the seat 42, preventing the passage of fuel from the chamber 26 into the mixing bowl 12. A stud 45 projects upwardly from the upper face of the head 44, positioned about which, in embracing relation, is one end of a spring 46, the other end of which engages a washer 46', against which may be threaded the screw 46'' for adjusting the tension of the spring 46.

Projected through the air intake portion 17 is a shaft 47 upon which is fixedly mounted a butterfly valve 48. Fixedly mounted upon the outer end of the shaft 47 is an operating arm 49, to the upper end of which is pivotally attached a rod 50 projected to a position easily accessible to the driver of the vehicle. The arm 49 is also connected by the link 51 to the free end of an arm 52 which is fixedly mounted upon the shaft 53 projecting into the bottom cap 18, and upon which is fixedly mounted a cam 54 adapted to engage the lower end of the shaft or stem 20.

The construction of these parts is such that when desired the operator of the vehicle may, by moving the rod 50 longitudinally, effect a rocking of the shaft 47 to

close the butterfly valve 48 and prevent entry of air into the carburetor through the air intake conduit 17. At the same time the shaft 53 is rocked so that the cam 54 moves the shaft or stem vertically upwardly to unseat the valve 44 from its seat 42 and permit passage of fuel from the chamber 26 into the chamber 12. This arrangement is provided for priming the engine when a rich mixture is desired.

A butterfly valve 55 is fixedly mounted upon a shaft 56 which is projected through the portion 14. Fixedly mounted upon the shaft 56 exterior of the carburetor is an arm 57 to which is pivotally connected an operating rod 58 directed to a position accessible to the operator of the vehicle, this rod 58 being commonly termed the throttle rod. The arm 57 is connected by the link 59 to an arm 60 which is fixedly mounted upon the stem 39 exterior of the carburetor. The connection of the link 59 with the arm 60 is effected by means of a stud or bolt 62 which is projected through a slot 61 formed in the link 59.

The structure is such that when the operator desires to move the throttle to feed fuel to the engine the butterfly valve 48 will normally be in the position shown in Fig. 1. When the operator starts the engine the butterfly valve 55 will be opened by operating the throttle rod 58. As the engine is started the suction from the engine will raise the disc 21 against the tension of the spring 23 to permit passage of air around the periphery of the disc, the ribs on the chamber 12 spacing the periphery of the disc 21 from the inner surface of the chamber 12, the disc 21 seating when in the position shown in Fig. 1 at the bottom of the chamber 12 and effectively closing this chamber against entry of air thereinto. As the suction raises the disc 21 off of its seat the air is permitted to pass through the air intake 17 and mix with the fuel in the mixing chamber 12 and in the delivery conduits 13 and 14. It is thus seen that as in the invention referred to in my previous application the delivery of fuel to the mixing chamber is controlled by the suction of the engine, the head 44 being slightly unseated as the disc 21 moves vertically upwardly. The fuel flowing into the chamber 26 will pass through the passage 31, the needle valve 36 being adjusted to permit the entry of the proper amount of fuel into this chamber.

As the speed increases and a larger amount of fuel is desired for consumption than will pass through the passage 31, the throttle rod 58 being moved a sufficient distance causes the pin 62 to engage the end of the slot 61, after which further movement of the throttle rod 58 will effect a longitudinal movement of the stem 39 so as to permit passage of fuel into the chamber 26 through 130

the passages 28 and 29. The needle valve 33 is previously adjusted to permit the passage of the desired amount of fuel through these passages 28 and 29.

5 With this arrangement there is provided a primary fuel inlet control and a secondary fuel inlet control, the secondary control being operated to permit the delivery of additional fuel to the engine only after the
10 fuel consumption of the engine has reached a certain degree so that when driving at low speeds a smaller amount of fuel is delivered to the engine than at higher speeds. Furthermore when the speed of the engine
15 reaches a certain degree to effect a proportionate increase in speed or power of the engine it is necessary that a larger proportionate amount be delivered to the engine and to effect this the auxiliary control is
20 brought into operation.

While I have illustrated and described the preferred form of structure I do not wish to limit myself to the precise embodiment of the structure shown, but desire to avail
25 myself of such variations and modification as come within the scope of the appended claim.

Having thus described my invention what I claim as new and desire to secure by Letters Patent is:

In a carburetor of the class described having a mixing chamber: a head having a fuel chamber formed therein adapted for communicating with said mixing chamber; control means for controlling communication of said fuel chamber with said mixing chamber; a fuel delivery pipe communicating with said fuel chamber through a primary passage; means for controlling communication of said primary passage with said fuel chamber, said head having a secondary passage formed therein communicating with said fuel chamber and with said delivery pipe; control means for controlling communication of said delivery pipe with said secondary passage; and other control means in axial alignment with said last mentioned control means for controlling communication of said secondary passage with said fuel chamber; a throttle rod; and means operable by said throttle rod for opening said other control means at predetermined positions of said throttle rod.

In testimony whereof I have signed the
55 foregoing.

PETER GWISDALLA.
